Primary Examiner—Cathron C Brooks*Assistant Examiner*—Austin Murphy*(74) Attorney, Agent, or Firm*—Osha • Liang LLP(57) **CLAIM**

The ornamental design for a coating film transfer tool, as shown and described.

DESCRIPTION

FIG. 1 is a front view of the coating film transfer tool design according to the present invention.

FIG. 2 is a rear view of the design according to the present invention.

FIG. 3 is a plan view of the design according to the present invention.

FIG. 4 is a bottom view of the design according to the present invention.

FIG. 5 is a left side view of the design according to the present invention.

FIG. 6 is a right side view of the design according to the present invention.

FIG. 7 is a front view of the design showing the head cover opened according to the present invention; and,

FIG. 8 is a front view of the design showing the head cover opened according to the present invention.

Portions of the invention shown in broken lines form no part of the claimed design.
